(57) CLAIM

The ornamental design for pier, as shown and described.

DESCRIPTION

FIG. 1 is a front elevational view of a pier showing my new design;

FIG. 2 is a front, left side perspective view, the right side begin a mirror image thereof;

FIG. 3 is a left side elevational view thereof; and,

FIG. 4 is a top plan view thereof.

The rear and bottom views are flat and unornamented. The broken lines shown throughout the views are for illustrative purposes only and form no part of the claimed design.

1 Claim, 4 Drawing Sheets
